RAILWAY TRAFFIC CONTROLLING APPARATUS

Application filed February 7, 1930. Serial No. 426,563.

My invention relates to railway traffic controlling apparatus, and particularly to apparatus of the type comprising train carried governing means controlled by energy received from the trackway.

The present case is a continuation in part of my co-pending application, Serial No. 238,572, filed Dec. 8, 1927, for railway traffic controlling apparatus, in so far as the subject matter common to the two applications is concerned.

I will describe several forms of railway traffic controlling apparatus embodying my invention, and will then point out the novel features thereof in claims.

In the accompanying drawings, Fig. 1 is a diagrammatic view showing one form of railway traffic controlling apparatus embodying my invention. Fig. 2 is a view showing a modified form of the train carried portion of the apparatus shown in Fig. 1. Fig. 3 is a view showing in front elevation one form of oscillator forming a part of the apparatus illustrated in Fig. 1. Figs. 4 and 5 are views showing in top plan and end elevation, respectively, the oscillator of Fig. 3. Fig. 6 is a vertical transverse sectional view along the lines VI—VI of Fig. 3. Fig. 7 is a view similar to Fig. 5, showing a modified form of a portion of the oscillator. Fig. 8 is a view showing a modified form of the apparatus illustrated in Figs. 1 and 2.

Similar reference characters refer to similar parts in each of the several views.

Referring first to Fig. 1, the reference characters 1 and 1^a designate the track rails of a stretch of railway track over which traffic normally moves in the direction indicated by the arrow. These rails are divided, by means of insulated joints 2, into a plurality of successive track sections, only one of which, A—B, is shown complete in the drawing. Train controlling current is supplied to the rails of this section from a suitable source of energy such as an alternate or G. The current supplied to the trackway by this alternator may be of a frequency of the order of the usual commercial alternating current, such for example as 60 cycles or 100 cycles per second.

The supply of current to the track rails is controlled by a coding device designated in general by the reference character X and comprising a plurality of rotatable cams each designated by the reference character C with a suitable distinguishing exponent. The cams C are driven at a constant speed by a suitable motor M which is supplied with current from the alternator G. The cam C¹ is provided with a plurality of swells spaced about its periphery and which swells successively engage a contact 3 to periodically close the contact as the cam C¹ is rotated. In similar manner the cams C² and C³ are provided with different numbers of swells which control contacts 4 and 5, respectively. One terminal of the alternator G is constantly connected with rail 1 of section A—B, and the other terminal of the alternator is connected with the rail 1^a through one of the contacts 3, 4, or 5, depending upon traffic conditions.

It is manifest that the alternating current supplied to the rails of the trackway by alternator G is periodically varied at the frequency of operation of the contact of the device X that is interposed between the alternator and the track rail 1^a. The coding device X may be constructed to cause such variations at any reasonable frequencies, but for purposes of illustration, I will assume that the cams C are rotating at 20 revolutions per minute, that cam C¹ has 4 swells, that cam C² has 6 swells, and that cam C³ has 9 swells. The selection between the several contacts of the coding device X in accordance with traffic conditions may be accomplished in any suitable manner such, for example, as by means of a home relay H and a distant relay L. The circuits for controlling these two relays form no part of my present invention and are omitted from the drawing for the sake of simplicity. For present purposes it is sufficient to state that home relay H is normally energized but is deenergized when a train occupies the section immediately to the right of point B. The distant relay L is also normally energized but is deenergized when a train occupies either the first or the second section.

immediately to the right of point B. With the apparatus thus far described, when relays H and L are both energized so that front contact 6-6^a of relay H and front contact 7-7^a of relay L are closed, current from alternator G, which current I will assume to be of 100 cycles per second, is supplied to the track rails over contact 5 operated by cam C³. Under these conditions the alternating current supplied to the trackway is periodically varied at a frequency of 180 cycles per minute. Current supplied to the trackway under these conditions, I will hereinafter term the "proceed code". When relay H is energized and relay L is deenergized, the closing of back contact 7-7^b of relay L includes contact 4 controlled by cam C² in the trackway circuit, and under these conditions the trackway is supplied with 100 cycle current interrupted at a frequency of 120 cycles per minute; this current I shall hereinafter term the "caution code". In similar manner when relay H is deenergized, the closing of back contact 6-6^b of this relay completes a circuit from alternator G to the track rails through contact 3 operated by cam C¹. Under these conditions the trackway is supplied with 100 cycle current interrupted at a frequency of 80 cycles per minute, which current I will call the "slow code".

The train indicated diagrammatically at V is provided with governing means which is responsive to the frequency of the periodic variations in the 100 cycle current supplied to the trackway. In the present embodiment of my invention the train is provided with two magnetizable cores 11 and 11^a located in advance of the forward axle 10 and disposed in inductive relation with the two track rails 1 and 1^a, respectively. Core 11 is provided with a winding 12, and a core 11^a is provided with a winding 12^a, the two windings 12 and 12^a being connected in series in such manner that the voltages induced therein by train controlling current flowing in opposite directions in the track rails at any instant are additive. Windings 12 and 12^a are connected, through an amplifier 13, and a transformer Q with a polarized relay R. When train controlling current is being supplied to the trackway, pulsating energy is delivered to the primary of transformer Q at the frequency of the periodic variations in such trackway current. For each impulse of current supplied to transformer Q, during the increase of such current, an impulse of one relative polarity is supplied to relay R and during the decrease of such current, an impulse of the opposite relative polarity is supplied to the relay. The relay R is responsive to the relative polarity of the current supplied thereto and it follows that when the train controlling current is supplied to the trackway is being periodically varied, the relay R is operated to close its normal and

reverse contacts 15-15^a and 15-15^b alternately at a frequency which corresponds to the frequency of the variations of the trackway current.

Associated with relay R is an oscillator 70 designated by the reference character K. Referring now also to Figs. 3 to 6 inclusive, the oscillator comprises a base 16 carrying an electromagnet E which operates a pivoted armature 19. A permanent magnet 18 extends from the back strap 17 of the electromagnet E to a position above the armature 19, for the purpose of polarizing the armature. The armature 19 constitutes one end of a driver P having two parallel side bars 20 and 21 and an end bar 90 pivoted in such manner that the driver is oscillated by oscillation of the armature 19. As shown in Fig. 1, when relay R is energized to close contact 15-15^a, current flows through one portion 80 of electromagnet E in one direction from battery D, thereby moving armature 19 in one direction. When relay R is reversed, however, to close contact 15-15^b, current from battery D flows through another portion of 90 electromagnet E in the opposite direction, thereby swinging armature 19 to the other limit of its stroke, and moving the driver P in the opposite direction. It will be plain, therefore, that when relay R is being operated 95 in accordance with any of the codes supplied to the trackway by coding device X, the driver P of the oscillator K will be swung to and fro at the speed at which the relay R is operating. 100

The oscillator K comprises also a plurality of fly wheels W¹, W² and W³, each pivotally mounted on suitable brackets on the base 16 and disposed coaxially in such position that the side bars 20 and 21 of the driver P extend through openings between the spokes of the wheels as best seen in Figs. 5 and 6. By means of helical springs 25, each of the side bars 20 and 21 of the driver P is attached to the rim of each of the wheels W at points adjacent the top of the wheel. When the driver P is at rest the two springs 25 acting upon each of the fly wheels W are balanced, so that the fly wheels then occupy positions of equilibrium. When the driver P of the oscillator K is being swung from side to side, however, a variable moment, the direction of which is reversed in synchronism with the operation of relay R, is applied to each of the fly wheels W. The fly wheels are constructed with different moments of inertia and the resiliency of the several springs 25 is so adjusted that each of the fly wheels W is mechanically resonant at the frequency of a different one of the codes supplied to the trackway. For example, I will assume that the fly wheel W¹ is mechanically resonant at 80 cycles per minute. If the 80 cycle code, hereinbefore termed the slow code, is supplied to the trackway, the driver P will be operated 110 at a frequency of 80 cycles per minute, and 115

120

125

130

the wheels W will be made to oscillate, through the springs 25, at the same frequency. Since the wheel W^1 is mechanically resonant at this frequency, the motion of this wheel builds up to a considerable value and the wheel W^1 swings through a comparatively large arc in synchronism with the driver P . The wheel W^2 is resonant at 120 cycles per minute and the wheel W^3 is mechanically resonant at 180 cycles per minute and it follows therefore that the motions of wheels W^2 and W^3 caused by oscillation of the driver P at 80 cycles per minute are comparatively small.

As best shown in Fig. 6, wheel W^3 carries a movable contact 24 which is arranged to engage alternately with two fixed contacts 24^a and 24^b at the limits of the motion of the wheel W^3 when this wheel is being oscillated at the frequency to which it is mechanically tuned. In similar manner the wheel W^1 operates contacts 22—22^a and 22—22^b and wheel W^2 operates contacts 23—23^a and 23—23^b.

From the foregoing explanation of the oscillator K , it will be apparent that all of the contacts operated by the oscillator are normally open but that when relay R operates at 80 cycles per minute in accordance with the slow code, contact 22 operated by wheel W^1 alternately engages contacts 22^a and 22^b. Under these conditions the contacts controlled by wheels W^2 and W^3 remain open. Similarly, if relay R is being operated at 120 cycles per minute or at 180 cycles per minute the contacts controlled by wheels W^2 and W^3 , respectively, are opened and closed in accordance with the code, the contacts controlled by the wheels which are not resonant at the frequency at which the oscillator is operated, remaining open.

Each of the wheels W is provided with damping mechanism here shown as a post 27^a attached to the wheel and cooperating with two fixed damping springs 27. When the wheel oscillates in either direction a polished face of the post 27^a engages one or the other of the damping springs 27. The damping mechanism causes the amplitude of oscillation of each wheel to diminish rapidly when the corresponding code ceases so that the oscillator responds rapidly to code changes. Furthermore the damping mechanism operates in a manner analogous to resistance in a tuned electrical circuit to broaden the tuning of the wheels so that each wheel will respond to code frequencies slightly different from the exact frequency to which the wheel is tuned. Still another function of the damping mechanism is to prevent operation of the contacts of each wheel by frequencies of one-third the frequency at which such wheel is resonant.

Referring now again to Fig. 1, the oscillator K controls three relays J^1 , J^2 and J^3 . Each of the relays J^2 and J^3 comprises two

windings 31 and 32 and is arranged to be slow-releasing. In explaining the operation of the apparatus I will first assume that the slow code is being supplied to the trackway so that the relay R is operating at 80 cycles per minute. Under these conditions the contacts 22—22^a and 22—22^b of oscillator K are alternately closed and the remaining contacts of the oscillator remain open. Each time contact 22—22^a is closed, current flows from battery D , through wires 33, 34, and 35, contact 22—22^b, wire 36, left-hand portion of primary 28 of a transformer T , and wires 37, 38 and 39, back to battery D . When the contact 22—22^b of oscillator K closes, current flows from battery D , through wires 33, 34 and 35, contact 22—22^b of oscillator K , wire 40, right-hand portion of primary 28 of transformer T and wires 37, 38 and 39, back to battery D . It follows therefore that when the oscillator K is being operated at 80 cycles per minute, the direction of the current supplied to primary 28 of transformer T is periodically reversed. The secondary 29 of transformer T supplies energy to relay J^1 through a rectifier 30 and it follows that this relay is energized when the slow code is being supplied to the trackway.

If the relay R is being supplied with the caution code, the contacts 23—23^a, and 23—23^b will be closed alternately, but the circuits just traced for transformer T will be open. Each time contact 23—23^a is closed, current flows from battery D , over wires 33, 34, 41, and 42, contact 23—23^a of oscillator K , wire 43, winding 31 of relay J^2 , wires 44 and 45, left-hand portion of primary 28 of transformer T and wires 37, 38 and 39 back to battery D . Each time the contact 23 swings in the opposite direction, current from battery D flows through wires 33, 34, 41 and 42, contact 23—23^b of oscillator K , wire 46, winding 32 of relay J^2 , wires 47 and 48, right-hand portion of primary 28 of transformer T and wires 37, 38 and 39, back to battery D . It follows, therefore, that when the oscillator K is being operated at 120 cycles per minute in accordance with the caution code, current is supplied alternately to the two windings of relay J^2 in series with the two halves of the primary 28 of transformer T . Under these conditions, therefore, relay J^2 is energized and relay J^1 is energized also, although the contacts operated by wheels W^1 and W^3 of oscillator K remain open. Similarly, when the proceed code is being received, contacts 24—24^a and 24—24^b are alternately closed and these contacts are effective to supply current to the two windings 31 and 32 of relay J^3 in series with the two halves respectively of primary 28 to transformed T over circuits which will be apparent from the drawing. When the proceed code is being received, therefore, relays J^1 and J^3 are energized and relay J^2 is deenergized.

Relays J^1 , J^2 and J^3 may be utilized to control train governing means in any suitable fashion and for purposes of explanation I have here shown these relays as controlling signal lamps 56, 62, 65 and 68. Assuming that the proceed code is being received, relays J^1 and J^3 are energized, as shown in the drawing. Under these conditions, current from battery D flows through wire 49, front contact 50—50^a of relay J^1 , wire 51, back contact 52—52^b of relay J^2 , wire 53, front contact 54—54^a of relay J^3 , wire 55, proceed lamp 56 and wires 57, 58, 59, 60, 38, and 39 back to battery D. Under these conditions the proceed lamp 56 is lighted to indicate that the proceed code is being received. When the caution code is being received, relays J^1 and J^2 are energized and relay J^3 is deenergized. Current then flows from battery D, over wire 49, front contact 50—50^a of relay J^1 , wire 51, front contact 52—52^a of relay J^2 , wire 61, caution lamp 62, and wires 63, 58, 59, 60, 38 and 39, back to battery D. If the slow code is being received, relay J^1 is energized and relays J^2 and J^3 are both deenergized and under these conditions the lamp 65 is lighted, the circuit for this lamp passing from battery D, through wire 49, front contact 50—50^a of relay J^1 , wire 51, back contact 52—52^b of relay J^2 , wire 53, back contact 54—54^b of relay J^3 , wire 64, lamp 65, and wires 66, 59, 60, 38 and 39 back to battery D. If no code is being supplied to the trackway, or if relay R is not being operated intermittently, or if for any other reason the supply of current to relay J^1 is interrupted, this relay closes its back contact 50—50^b, and thereby completes a circuit for the lamp 68 to indicate stop. The circuit for lamp 68 will be readily understood from the drawing without tracing the circuit in detail.

In the modified form of apparatus shown in Fig. 2, the circuits for relays J^2 and J^3 and for primary 28 of transformer T controlled by contacts 23 and 24 are the same as in Fig. 1. Contacts 22—22^a and 22—22^b of the oscillator K are omitted, however, and the transformer T is provided with auxiliary circuits controlled directly by the relay R in place of the circuits controlled by contact wheel W^1 in Fig. 1. Thus when the apparatus shown in Fig. 2 is receiving the caution or proceed codes, the operation is exactly the same as has already been described in connection with Fig. 1. When the relay R is being operated in accordance with the slow code, however, the contacts controlled by both wheels W^2 and W^3 are open so that relays J^2 and J^3 are deenergized. But each time contact 15—15^a is closed, current from battery D flows through wire 33, contact 15—15^a, wires 70 and 71, back contact 72 of relay J^2 , wire 73, back contact 74 of relay J^3 , wires 75 and 36, left-hand portion of primary 28 of transformer T, and wires 37, 38, and 39,

back to battery D. When relay R next reverses to close its contact 15—15^b, current from battery D flows through wire 33, contact 15—15^b, wires 76 and 77, back contact 78 of relay J^2 , wire 79, back contact 80 of relay J^3 , wires 81 and 40, right-hand portion of primary 28 of transformer T and wires 37, 38 and 39, back to battery D. It follows, therefore, that when relay R is being operated at the frequency of the slow code, the alternating current induced in secondary 29 of transformer T energizes relay J^1 . The parts may be so proportioned that if the frequency of operation of relay R drops materially below the frequency of the slow code, the amount of energy supplied to relay J^1 will not be sufficient to keep this relay in its energized condition.

It will be plain that the selection between the relays J^1 , J^2 and J^3 in accordance with the several codes is the same in Fig. 2 as in Fig. 1 and the control of the signal lamps 68, 65, 62 and 56 by the relays J is the same as in Fig. 1 and will be understood without further explanation.

The apparatus may be constructed to permit the oscillator K to perform the functions of the relay R. For example, as shown in Fig. 7, the armature 19 carries a contact finger 95 which is electrically insulated from the armature and which is arranged to swing alternately into engagement with two fixed contacts 95^a and 95^b when the armature is oscillated. With the oscillator constructed in this manner, the parts may be connected as shown in Fig. 8, from which it will be apparent that the electromagnet E which operates the oscillator is connected directly with the secondary of transformer Q. It follows that when the train controlling current supplied to the trackway is being periodically varied, the armature 19 of oscillator K will be swung to and fro at the frequency of the variations in the trackway current.

The circuits for relays J^2 and J^3 and for the primary 28 of transformer T controlled by contacts 23 and 24 are the same as in Figs. 1 and 2, and the operation of the apparatus in response to the proceed and caution code will be understood without further explanation. When the apparatus shown in Fig. 8 is receiving the slow code, however, the armature 19 is driven at a rate so slow that the contacts operated by 23 and 24 remain open, and relays J^2 and J^3 are deenergized.

Each time the armature swings in one direction, contact 95—95^b is closed and current flows from battery D, through wires 33 and 91, contact 95—95^b operated by oscillator K, wire 71, back contact 72 of relay J^2 , wire 73, back contact 74 of relay J^3 , wires 75, 92 and 48, right-hand portion of primary 28 of transformer T, and wires 37 and 38 back to battery D. When the armature 19 swings in the opposite direction, a circuit is completed

from battery D, through wires 33 and 91, contact 95—95^a operated by oscillator K, wire 77, back contact 78 of relay J², wire 79, back contact 80 of relay J³, wires 81, 45 and 36, 5 left-hand portion of primary 28 of transformer T, and wires 37 and 38 back to battery D. The periodically reversed current thus supplied to transformer primary 28 during reception of the slow code energizes relay J¹ and under these conditions lamp 65 is lighted. The remaining lamps 68, 62 and 56 are controlled by the relays J¹, J² and J³ in the same manner as in Figs. 1 and 2.

It will be plain from the foregoing, that 15 with the apparatus constructed as shown in Fig. 8, the magnet E and its armature 19 not only drive the fly wheels of the oscillator, but also perform the functions of the relay R shown in Figs. 1 and 2.

20 I make no claim, in the present case, to the structure of the oscillator K, this device being claimed per se and in combination with apparatus for intermittently supplying current to a load, in my copending application Serial No. 426,565, filed on even date herewith.

25 Although I have herein shown and described only a few forms of railway traffic controlling apparatus embodying my invention, it is understood that various changes and modifications may be made therein within the scope of the appended claims without departing from the spirit and scope of my invention.

Having thus described my invention, what 30 I claim is:

1. Railway traffic controlling apparatus comprising means for supplying the trackway with alternating current periodically varied at different frequencies, a plurality of train carried contacts operated by energy received from the trackway and selectively responsive to the frequency of such periodic variations, a plurality of relays one controlled by each said contact and one of such 45 relays controlled by all such contacts, and governing means controlled by said relays.

2. Railway traffic controlling apparatus comprising means for supplying the trackway with alternating current periodically varied at different frequencies, a train carried oscillator operated by energy received from the trackway and having a plurality of contacts selectively responsive to the frequency of such periodic variations, a plurality of relays one controlled by each of 55 said contacts and one of such relays being controlled by all said contacts, and governing means controlled by said relays.

3. In combination, a source of alternating 60 current, means for periodically varying the current from said source at different frequencies, a relay receiving energy from the source and responsive to the variations in such current but not to the current itself, an oscillator comprising a plurality of contacts each

arranged to be operated when and only when the relay is operating at a predetermined frequency which is different for each contact, a first relay arranged to be energized when any of said contacts is operating, other relays 70 each arranged to be energized when a predetermined one of such contacts is being operated, and governing means controlled by said relays.

4. In combination, a first relay, means for operating said first relay intermittently at different frequencies, a first contact arranged to be operated when the relay is operating at one frequency, a second contact arranged to be operated when the relay is operating at a different frequency, a transformer, two other relays, means controlled by each said contact for supplying periodic current to the primary of said transformer in series with a winding of an associated one of such other relays, a fourth relay receiving energy from the secondary of said transformer, and governing means controlled by said two other relays and by said fourth relay. 75

5. In combination, two contacts, means for at times operating one contact and for at other times operating the other contact, two relays, a transformer, means effective when said one contact is operated to supply periodic current to the primary of said transformer in series with a winding of one relay, means effective when said other contact is operated to supply periodic current to said primary in series with a winding of the remaining relay, a third relay receiving energy from the secondary of said transformer, and indicating means controlled by said three relays. 90

6. Railway traffic controlling apparatus comprising means for supplying the trackway with alternating current periodically varied at different frequencies, a train carried oscillator operated in accordance with energy received from the trackway and comprising two normally open contacts arranged to be closed intermittently when and only when said alternating current is being interrupted at a predetermined frequency, a relay having two windings, a circuit for one winding of the relay including one of said contacts, a circuit for the other winding of the relay including the remaining contact, and governing means controlled by said relay. 105

7. Railway traffic controlling apparatus comprising means for supplying the trackway with alternating current periodically varied at different frequencies, a train carried oscillator operated in accordance with energy received from the trackway and comprising two pairs of normally open contacts and means for alternately closing the contacts of one pair of contacts or the other depending upon the frequency of said variations, a relay comprising two windings associated with each pair of contacts, a trans- 110

former; two circuits for each relay each including one winding of such relay, one contact of the associated pair, and a portion of the primary of said transformer; a third relay receiving energy from the secondary of said transformer, and governing means controlled by said three relays.

8. Railway traffic controlling apparatus comprising means for supplying the trackway with alternating current periodically varied at different frequencies, a main relay receiving energy from the trackway and operating at a frequency which depends upon the frequency of such variations, an oscillator controlled by said main relay and comprising a plurality of contacts selectively responsive to the frequency of operation of the main relay, a second relay controlled by all said contacts, a plurality of other relays each controlled by one of said contacts, and governing means controlled by said second relay and by said other relays.

9. Railway traffic controlling apparatus comprising means for supplying the trackway with alternating current periodically varied at different frequencies, a main relay receiving energy from the trackway and operating at a frequency which depends upon the frequency of such variations, an oscillator controlled by said main relay and comprising a plurality of contacts selectively responsive to the frequency of operation of the main relay, a series of relays each controlled by an associated one of such contacts; an additional relay controlled by all said contacts, by said main relay, and by all the relays in such series, and governing means controlled by said additional relay and by the relays of said series.

10. Railway traffic controlling apparatus comprising a train carried oscillator having an armature and a plurality of contacts selectively responsive to the frequency of operation of said armature, means located partly in the trackway for operating said armature at different frequencies, a first relay controlled by one said contact, a second relay controlled by all said contacts, and governing means controlled jointly by said two relays.

11. Railway traffic controlling apparatus comprising a train carried oscillator having an armature and a plurality of contacts selectively responsive to the frequency of operation of said armature, means located partly in the trackway for operating said armature at different frequencies, a first relay controlled by all said contacts, a plurality of other relays each controlled by a different one of said contacts, and governing means controlled by said first relay and by said other relays.

12. Railway traffic controlling apparatus comprising a train carried oscillator having a movable armature, means located partly in the trackway for operating said armature at

different frequencies, a plurality of contacts operated mechanically by said armature and selectively responsive to the frequency of operation of such armature, an additional contact operated by said armature, and governing means controlled by all said contacts.

13. Railway traffic controlling apparatus comprising a train carried oscillator having a movable armature, means located partly in the trackway for operating said armature at different frequencies, a plurality of contacts operated mechanically by said armature and selectively responsive to the frequency of operation of such armature, a plurality of relays each controlled by a different one of said contacts, an additional relay controlled directly by said armature, and governing means controlled by all said relays.

14. Railway traffic controlling apparatus comprising means for supplying the trackway with alternating current periodically varied at different frequencies, a train carried oscillator having an armature operated by energy received from the trackway at a frequency which depends upon the frequency of variation of the trackway current, a plurality of contacts on said oscillator selectively responsive to the frequency of operation of said armature, a first relay controlled by all said contacts, a plurality of other relays each controlled by a different one of said contacts, and governing means controlled by said first relay and by said other relays.

15. Railway traffic controlling apparatus comprising means for supplying the trackway with alternating current periodically varied at different frequencies, an oscillator having a plurality of contacts selectively responsive to the frequency of the variations in the trackway current, a first relay controlled by all said contacts, a plurality of other relays each controlled by a different one of said contacts, and governing means controlled by said first relay and by said other relays.

16. In combination, a source of alternating current periodically varied at different frequencies, an oscillator controlled by energy received from said source and comprising a plurality of contacts selectively responsive to the frequency of the variation in such current, a first relay controlled by all said contacts, a plurality of other relays each controlled by a different one of said contacts, and governing means controlled by said first relay and by said other relays.

In testimony whereof I affix my signature.
ANDREW J. SORENSEN.
